ANTENNA SYSTEM

Oakley M. Woodward, Jr., Princeton, N. J., assignor to Radio Corporation of America, a corporation of Delaware

Application August 10, 1944 Serial No. 548,817

11 Claims. (Cl. 250—33.53)

1

This invention relates to radio antennas, and more particularly to antenna systems for providing horizontal uniform omnidirectional field patterns, with predetermined vertical directivity and uniform polarization.

The principal object of the present invention is to provide an improved type of antenna system which may be designed to provide a field pattern which is substantially uniform horizontally.

Another object is to provide a system of the described type which will radiate and respond to substantially only horizontally polarized energy.

A further object of the invention is to provide a system of the described type which may be designed to provide any desired degree of elevational directivity.

A still further object is to provide an antenna system of relatively simple construction which may be designed readily to exhibit the required characteristics of uniform horizontal directivity and horizontal polarization.

These and other objects will become apparent to those skilled in the art upon consideration of the following description, with reference to the accompanying drawing, of which

Figure 1 is a schematic plan view of a prior art antenna of the general type to which this invention relates,

Figure 2 is an elevation of the antenna of Figure 1,

Figure 3 is a schematic plan view of an antenna constructed in accordance with the present invention,

Figure 4 is an elevation of the antenna of Figure 3,

Figure 5 is a graph in polar coordinates illustrating the field patterns provided by the antennas of Figures 1 and 3, and

Figure 6 is a partial section illustrating the mechanical details of construction of the antenna of Figures 3 and 4.

Referring to Figures 1 and 2, a typical prior art antenna for providing horizontal polarization comprises a plurality of stacked layers 1, 2, 3 and 4, each comprising four horizontal dipoles 5, 6, 7 and 8 spaced uniformly around a cylindrical conductive support 9. Although the dipoles 5, 6, 7 and 8 are represented by single lines, it is to be understood that each includes a pair of collinear conductors disposed end to end with the adjacent ends connected to the respective terminals of a transmission line, as described below with reference to Figure 6. It is sufficient for the present to say that the radiators are all connected effectively in parallel to operate in phase, so that the currents all flow in the same direction simultaneously, that is all clockwise or all counter-clockwise if viewed from the top, as indi-

cated by the arrows in Figure 1. The layers 1, 2, 3 and 4 are spaced vertically along the support 9 at intervals of one-half wavelength. The elevational directivity of the system is determined in accordance with principles well known to those skilled in the art, by the number of such layers. Each of the dipoles is spaced one-quarter wavelength radially from the surface of the support 9.

The field intensity in a horizontal plane produced by the above-described antenna with a current I in each of the radiator elements is

$$(1) E = -j4k(W_0 + 2W_4 \cos 4\phi + 2W_8 \cos 8\phi + 2W_{12} \cos 12\phi + \dots)$$

where k is a constant, $W_0, W_4, W_8, \dots, W_n$ are coefficients depending upon the radius a of the support 9 and the radial distance b of each radiator from the center of the support 9, and ϕ is the angle with respect to a reference line extending diametrically across the array through two of the radiators, as indicated in Figure 1. In the described structure where A is $.3\lambda$ and B is $.55\lambda$, all of the terms of Equation 1 following the second term are negligibly small, hence,

$$(2) E = -j4k(W_0 + 2W_4 \cos 4\phi)$$

The corresponding horizontal directivity pattern of the antenna of Figure 1 is illustrated by the curve designated E on the polar graph of Figure

30 5. The maximum field intensity is arbitrarily designated as F. It is evident that the field is not uniform, but varies approximately 30 percent, from .707 F to 1 F.

The principle of the instant invention lies in superimposing upon the pattern of Figure 5 a similar pattern, displaced at an angle of 45° with respect thereto. Referring to Figures 3 and 4, an array constructed in accordance with the present invention comprises layers 10, 11, 12, 13 of radiators similar to the layers 1, 2, 3 and 4 of Figure 2, with successive layers displaced horizontally through an angle of 45° . Thus the radiators of the layer 10 are parallel to the respective corresponding radiators of the layer 12, and at an angle of 45° to the respective corresponding radiators of the layers 11 and 13. As in the system of Figures 1 and 2, all of the radiators are operated in phase. With a current I flowing in each radiator, the field intensity in a horizontal plane produced by the layers 10 and 12 is

$$(3) E' = \frac{-j4k(W_0 + 2W_4 \cos 4\phi)}{2}$$

55 and is identical in shape to that produced by the antenna of Figure 1. The field intensity provided by the layers 11 and 13 is

$$(4) E'' = \frac{-j4k[W_0 + 2W_4 \cos 4(\phi - 45^\circ)]}{2}$$

but

$$(5) \quad \cos 4(\phi - 45^\circ) = -\cos 4\phi$$

therefore

$$(6) \quad E'' = \frac{-jk(W_0 - 2W_4 \cos 4\phi)}{2}$$

adding the fields E' and E'' :

$$(7) \quad E_t = E' + E'' = -jk8W_0$$

It is apparent that E_t is independent of the angle ϕ , and is therefore horizontally uniform. Any number of pairs of layers similar to the pairs 10, 11 and 12, 13 may be employed to provide any desired degree of vertical directivity.

Referring to Figure 6, a preferred mechanical structure of the radiator elements is illustrated. The supporting conductor 9 is provided with a plurality of holes in which short cylindrical sleeves 14 are secured, extending radially outward from the surface of the conductor 9. The sleeves 14 are adapted to receive with a press fit tubular members 15. Each of the members 15 is provided with a shoulder 16 for engagement with the outer end of the sleeve 14 and carry at its outer end a pair of collinear conductors 17 and 18. A pair of slots 19 are formed in the member 15, extending radially inward toward the shoulder 16 forming a slot of a length hereinafter specified. The slots 19 lie in a plane at right angles to the members 17 and 18. A conductor 21 is supported coaxially within the member 15 by an insulator 22, and terminates at its inner end near the surface of a conductor 23. A conductor 23 is supported coaxially within the conductor 9. The outer end of the conductor 21 is bent at right angles and connected to the member 15 at its outer end at the point 24.

Figure 6 shows only a portion of a single layer of radiator elements. The remainder of the elements of this layer, as well as those of the other layers, are identical in construction with those which are illustrated. However, the dipoles of each layer are physically reversed in position with respect to those of the adjacent layers, in order to provide in-phase excitation of all of the dipoles, with one-half wave spacing between adjacent layers. The instant invention is not limited to a specific dipole structure, which is illustrated merely to show one embodiment thereof.

The lower ends of the conductors 9 and 23 may be connected to a translation device such as a radio receiver or transmitter. The inner conductor 23 is coupled to the conductors 21 by virtue of the capacitance existing between the inner ends of the conductors 21 and the surface of the conductor 23. Assuming a voltage to be applied between the conductors 9 and 23, current flows through this capacitance and through the conductor 21 to the wall of the member 15 adjacent the element 17, thence through the wall to the conductor 9. The flow of current through the conductor 21 induces a voltage between the lower end of the member 15 and the upper end at the point of connection of the radiator 18, causing current to flow in from the radiator 18 while current is flowing out on the radiator 17, and vice versa.

The slots 19 are somewhat less than one-quarter wavelength long. The two portions of the conductor 15 separated by the slots 19 function as a transmission line shorted at its lower end, providing an inductive reactance between the inner ends of the members 17 and 18. The members 17 and 18 are each somewhat less than one-quarter wavelength long, providing a capacitive

reactance substantially equal to said inductive reactance at the frequency of operation of the system. Thus the conductors 17 and 18 are effectively insulated from each other at this frequency, owing to parallel resonance of the inductive reactance between the slots 19 and the capacitive reactance of the conductors 17 and 18.

Although the invention has been described with reference to a specific type of radiator structure, it is to be understood that any type or radiator may be employed, subject only to the limitation that pairs of layers of four radiators equally spaced around a circular conductive support are used, with the radiators of one layer displaced horizontally 45° with respect to those of the other layers. This arrangement provides a directive pattern which is uniform throughout the horizontal plane, providing the diameter of the circular support is substantially .6λ and the radiators are spaced substantially .25λ from the surface of the support. The above dimensions may be changed throughout a limited range without serious distortion of the desired circular pattern.

I claim as my invention:

25. 1. An antenna system comprising a vertical conductive support and at least one pair of horizontal layers of radiator elements, each layer comprising four elements spaced radially from said support and disposed at equal horizontal intervals around said support, with the elements of one layer of each pair staggered horizontally by an angle of 45° with respect to those of the other layer of said pair means interconnecting said elements so that the currents in all of said 30 elements in all of said layers are in time phase with each other.

2. An antenna system comprising a cylindrical conductive vertical support and a plurality of horizontal layers of radiator elements, each layer comprising four elements spaced radially from said support and disposed at equal intervals around said support, with the elements of each layer staggered horizontally by an angle of 45° with respect to those of each adjacent layer means interconnecting said elements so that the currents in all of said elements in all of said layers are in time phase with each other.

3. An antenna system comprising a cylindrical conductive vertical support and a plurality of pairs of horizontal layers of radiator elements, each layer comprising four elements spaced radially from said support disposed at 90° intervals around said support, with the elements of one layer of each pair displaced horizontally 45° with respect to the corresponding elements of the other layer of said pair means interconnecting said elements so that the currents in all of said elements in all of said layers are in time phase with each other.

4. An antenna system comprising a cylindrical conductive vertical support and at least one pair of horizontal layers of radiator elements, each layer comprising four elements spaced radially from said support and disposed at 90° intervals around said support, with the elements of one layer of each pair displaced horizontally 45° with respect to the corresponding elements of the other layer of said pair means interconnecting said elements so that the currents in all of said elements in all of said layers are in time phase with each other.

5. An antenna system comprising a hollow cylindrical vertical conductor substantially .6 wavelength in diameter at the frequency at which the system is to operate, at least one pair of hori-

zontal layers, spaced vertically apart substantially one-half wavelength, of radiator elements, each layer comprising four elements disposed at 90° intervals horizontally around said support and substantially one-quarter wavelength distant radially from the surface of said support, with the elements of one layer of each pair displaced horizontally 45° with respect to the corresponding elements of the other layer of said pair, conductor means extending coaxially within said hollow conductor, and means for coupling the radiator elements of each of said layers to said conductors at substantially one-half wavelength intervals thereon, whereby all of said radiator elements are effectively connected in parallel for operation in phase.

6. The invention as set forth in claim 5, wherein in each of said radiator elements includes a horizontally disposed linear conductor.

7. The invention as set forth in claim 5, wherein in each of said radiator elements comprises a horizontal dipole and the dipoles of each layer are orthogonally disposed with respect to each other.

8. The invention as set forth in claim 5, wherein in each of said radiator elements comprises a dipole.

9. An antenna system comprising a hollow vertical conductor, at least one pair of horizontal layers, spaced vertically apart substantially one-half wavelength, of radiator elements, each layer comprising four elements disposed at 90° intervals horizontally around said support with the elements of one layer of each pair displaced horizontally 45° with respect to the corresponding elements of the other layer of said pair, conductor means extending coaxially within said hollow conductor, and means for coupling the radiator elements of each of said layers cophasally to said conductors the connections of each layer being reversed with respect to those of the adjacent layers to provide cophasal operation of all of said radiator elements.

10. An antenna system comprising a cylindrical vertical conductor substantially .6 wavelength in diameter at the frequency at which the system is to operate, at least one pair of horizontal layers of radiator elements, each layer comprising four elements disposed at 90° intervals horizontally around said support and substantially one-quarter wavelength distant radially from the surface of said support, with the elements of one layer of each pair displaced horizontally 45° with respect to the corresponding elements of the other layer of said pair.

11. An antenna system comprising a vertical conductor, at least one pair of horizontal layers of radiator elements spaced vertically apart, each layer comprising four elements spaced radially from said support and disposed at 90° intervals horizontally around said support with the elements of one layer of each pair displaced horizontally 45° with respect to the corresponding elements of the other layer of said pair, and means interconnecting all of said radiator elements so that the currents in all of said elements in all of said layers are in time phase with each other.
